DESIGN FOR A PAPER DISH

James D. Reifsnyder, Flushing, N. Y., assignor to Lily-Tulip Cup Corporation, New York, N. Y., a corporation of Delaware

Application December 31, 1946, Serial No. 135,882

Term of patent 14 years

(Cl. D44—9)

To all whom it may concern:

Be it known that I, James D. Reifsnyder, a citizen of the United States and a resident of Flushing, New York, whose post-office address is 3334 158th Street, Flushing, in the county of Queens and State of New York, have invented a new, original, and ornamental Design for a Paper Dish, of which the following is a specification, reference being had to the accompanying drawing, forming part thereof, wherein:

Fig. 1 is a somewhat enlarged plan view of a paper dish embodying my new design;

Fig. 2 is a side elevational view of the paper dish shown in Fig. 1; and

Figs. 3 and 4 are sectional views taken respectively at 3—3 and 4—4 of Figs. 1 and 3, showing further details of said design on a scale somewhat further enlarged.

I claim:

The ornamental design for a paper dish, substantially as shown.

JAMES D. REIFSNYDER.
